DRILL CABINET

Bernard Leonard Polkosnik, Bridgeport, Conn.,
assignor to Abraham Rosenberg, New York,
N. Y.

Application April 8, 1940, Serial No. 328,499

3 Claims. (Cl. 206—17)

The present invention relates to drill cabinets and more particularly to the portable type.

The principal object of this invention is to provide a drill cabinet of novel and improved construction, which is compact when closed, and upon merely opening the cabinet, rows of drills housed therein, are automatically shifted into such position that each drill becomes readily displayed and easily and individually accessible, and upon closing of said cabinet, said rows of drills automatically shift into superimposed relation to effect such a desired compact article.

A further object hereof is to provide a drill cabinet of the character set forth of novel and improved construction which is reasonably cheap to manufacture, convenient to use, certain in its automatic actions aforementioned and efficient in carrying out the purposes for which it is designed.

Other objects and advantages will become manifest as this disclosure proceeds. In the accompanying drawings, comprising part of this application, similar characters of reference indicate corresponding parts in all the views.

Fig. 1 is a side view of drill cabinet embodying the teachings of this invention; said drill cabinet being shown fully opened.

Fig. 2 is a top view of Fig. 1.

Fig. 3 is a view similar to Fig. 1 showing said embodiment when the cabinet is fully closed.

Fig. 4 is a similar view, partly in section, showing said embodiment when the cabinet is either partially open or partially closed, and particularly showing the components of the device in their relative positions which they assume at this time.

Fig. 5 is a front view of one of the drill racks included in said embodiment.

Figs. 6 and 7 are in perspective, and show components employed in this device, which serve to automatically position, space, and secure the several drill racks included in said embodiment and to indicate drill sizes in convenient fashion with respect to the many drills within the cabinet.

In the drawings the numerals 15 and 16 constitute a pair of telescopic box members in hinged relation at one of their respective ends, at 17. Member 15, which is the inner one, is provided with slots 18 at its remote free side ends so that front flange 15' so formed may clamp with the front wall 16', to maintain the box or cabinet in closed condition and yet easy to be opened. Provision is made so that member 15 can move but a little more than a right angle; edge 15" serving as a stop.

Depending upon the drill capacity desired of

the cabinet, a suitable number of tray members, (in the present embodiment three of such being included), namely those indicated by the numerals 19, 20, and 21, are each mounted pivotally near their lower ends between the side walls of box section 16, along axis provided at 22, 23, and 24, respectively, all parallel to the axis at 17. Each of these tray members have a series of drill sockets 25 therein, preferably of increasing depth as indicated in Fig. 5; the dimensions of said tray members and the drill sockets therein being such that the cabinet formed by the box sections 15 and 16 may close as in Fig. 3, housing therein said drill trays 19, 20, and 21, with their full sets of drills indicated generally by the numerals 26, 27, and 28.

The bottom of each of the drill trays 19, 20, and 21 is so tapered or shaped as at 19', and 20', and 21', so that wall 15" of what may be called the cabinet door 15, acts as a stop, and due to gravity, as said door 15 is opened, the drill trays will assume relative substantially, radially spaced positions as indicated in Fig. 1.

However, in such set up, meaning minus the members of Figs. 6 and 7, each of said drill trays 19, 20, and 21, is free to be moved individually towards the door 15. As a further improvement therefore, I provide near the top of each said drill trays, except the one first to enter the box section 16, and as applied to the embodiment shown, near the top of each of the drill trays 20, and 21, is a hingedly mounted shelf member indicated by the numeral 29, in one instance and by the numeral 30 in the other, the respective axis of such hinged or pivoted connections being indicated by the numeral 29' and 30'. Forward of shelf 30, preferably at each end thereof, extends an arm 30" which connects as a hook to engage the drill tray 20. Likewise forward of shelf 29, preferably at each end thereof, extends an arm 29" which acts as a cam in a manner hereafter explained. It is evident that, as in Fig. 1, the drill trays 19, 20, and 21 are associated in a more stable set up when said shelves 29 and 30 and their associated arms are included in the device. Said shelves may be utilized to carry drill size indications corresponding to adjacent drill sockets as shown in the Figs. 2, 6 and 7. In operation, to open the cabinet it is rested on box section 16 while cover 15 is swung upwardly from its position in Fig. 3, until it reaches its final rest position as in Fig. 1. It is to be noted that no other parts of the device need be touched to effect the shifting of the various interior

components because such is accomplished automatically as follows:

Referring to the Fig. 4, which shows a partially opened position of the cabinet, the drill trays 19, 20, and 21 and the shelves 29 and 30 will all droop downward due to gravity and the drills of series 26 will glide along the floor of the cabinet member 16 as will cam 29', while hooks 30' will glide along the shelf 29 until the amount of swing of the cabinet cover 15 is sufficient so that said hooks engage the drill tray 20 while shelf 29 will set itself between the drill trays 19 and 20 and then, successively, the movement of the respective drill trays 19, 20, and 21 will be stopped by the door member 15 because of the beveled or other shaped bottoms of said drill trays. The device, now opened as in Fig. 1, displays all of the drills and each of them are readily accessible for withdrawal from their respective sockets and likewise easily replaceable therein.

In closing the cabinet, only the door 15 is swung to its position, as in Fig. 4, and then finally as shown in Fig. 1, during which travel said door 15 at first carries along with it all the drill trays 19, 20, and 21, set up, spaced and associated as in Fig. 1, until tab 29' comes into contact with the floor cabinet section 16 whereupon shelf 29 is automatically swung upwardly thereby shifting hook 30' also upwardly, thus releasing the drill tray 21. All the parts are now free to automatically assume the position as illustrated in Fig. 3, which they do as the cabinet finally is fully closed.

As modifications, the drill tray 20, for instance, may be relieved of that portion thereof under line A, and the interior cabinet components shall consist of either 20, 30 and 21, or else, 19, 29 and 20. In fact only one of the drill trays need have such lower portion to act as a stop against 15'', and depending which one that is, so will we need choose properly the members 29 and 30, for in some instances spacers 29 will suffice, and in others, the hooking feature of member 30 becomes necessary.

This invention is capable of numerous forms and various applications without departing from the essential features herein disclosed. It is therefore intended and desired that the patent shall cover whatever features of patentable novelty are herein disclosed; reference being had to the following claims rather than to the specific embodiments shown and described herein to indicate the scope of this invention.

I claim:

1. In a drill cabinet of the character set forth, a box member, a cover member hinged thereto, a number of drill trays positioned between the box and cover members, pivotally mounted near their lower ends to the cover member along spaced non-collinear axes respectively; all such axes being parallel to the line of the cover hinge connection and forward of each other; each drill tray having a point at its bottom at a greater distance from the axis of its pivotal connection, than the shortest distance from said axis to the cover member, whereby upon opening the cabinet by an upward swing of the cover member, the drill trays will automatically assume spaced and relatively radial positions, and upon closing of the cabinet by a downward swing of the cover member, said drill trays will be automatically

swung towards each other and become housed within the cabinet.

2. In a drill cabinet of the character set forth, a box member, a cover member hinged thereto, 5 a drill tray positioned between said members, pivotally mounted near its lower end to the cover member along an axis parallel to the line of the cover hinge connection; said tray having a point at its bottom at a greater distance from the axis of its pivotal connection, than the shortest distance from said axis to the cover member, a second drill tray positioned between the first drill tray and the cover member, pivotally mounted at its lower end to the cover member along an axis 10 parallel to the line of the cover hinge connection and forward of the axis of the pivotal connection of the first drill tray, and a spacer member positioned between said trays, hinged at one end to the second drill tray along an axis 15 parallel to the line of the cover hinge connection, and having a forward element adapted to extend beyond the first drill tray; whereby upon opening the cabinet by an upward swing of the cover member, the spacer member will automatically fall between the drill trays and serve as a spacer between them, and the drill trays will automatically assume spaced and relatively radial positions, and upon closing of the cabinet by a downward swing of the cover member, said 20 forward element of the spacer member, upon contacting any component of the drill cabinet, will be automatically shifted upwards, whereupon the drill trays will be automatically swung towards each other and become housed within the cabinet.

3. In a drill cabinet of the character set forth, a box member, a cover member hinged thereto, a drill tray positioned between said members, pivotally mounted near its lower end to the cover member along an axis parallel to the line of the cover hinge connection; said tray having a point at its bottom at a greater distance from the axis of its pivotal connection, than the shortest distance from said axis to the cover member, a second drill tray positioned between the first drill tray and the box member, pivotally mounted at its lower end to the cover member along an axis 25 parallel to the line of the cover hinge connection and forward of the axis of the pivotal connection of the first drill tray, and a spacer member positioned between said trays, hinged at one end to the first drill tray along an axis parallel to the line of the cover hinge connection, and having a forward hook element adapted to extend beyond the second drill tray and engage same in hook fashion, whereby upon opening of the cabinet by an upward swing of the cover member the spacer member will automatically fall between the drill trays and serve as a spacer between them and the drill trays will automatically assume spaced and relatively radial positions and become secured to one another by said hook element, and upon closing of the cabinet by a downward swing of the cover member, said hook element upon contacting any component of the drill cabinet, will be automatically shifted upwards, whereupon the drill trays will be automatically swung towards each other and become housed within the cabinet.
